CONTROLLING INDUCTION-MOTORS.

1,245,993.

Specification of Letters Patent. Patented Nov. 6, 1917.

Application filed February 3, 1914. Serial No. 816,228.

To all whom it may concern:
Be it known that I, RICHARD VAN R. SILL, of the city of New York, in the county of New York and State of New York, have invented certain new and useful Improvements in Controlling Induction-Motors; and I do hereby declare the following to be a full, clear, and exact description of the invention, such as will enable others skilled in the art 10 to which it appertains to make and use the same.

In order to properly control polyphase induction motors, it is desirable that in cutting out the resistance the speed should be 15 increased uniformly and not in jerks or irregular jumps.

When the circuits for each phase are balanced, that is, the resistors in circuit with the several phases are equal, it is usual to 20 have the first section of each resistor of greater resistance than the following sections. When these sections are cut out successively, the speed increases varyingly, that is, not uniformly. The first section being of 25 unequal resistance relatively to the next two, the speed increase is not as great in proportion when the first section is cut out as when the second is cut out, and likewise, not as great when the second is cut out as when the 30 third is cut out. When the fourth section is cut out the resistance of the different sections being less than that of the former sections, there is a jump in the speed of the motor. This renders alternating current motors as 35 heretofore constructed unavailable for certain kinds of work, such as hoists for elevating and setting girders and stone and on lathes where variable speeds are required.

I have overcome this difficulty by maintaining the resistances in circuit with the several phase windings unbalanced throughout the period of acceleration. In other words all the circuits have not the same degree of resistance. The phase windings are 45 continuously connected to their resistances and I shift the resistance from one phase circuit to another.

The accompanying drawing shows a diagrammatic sketch of a method of control embodying my invention. 1 represents the resistance as an entirety, the parts thereof being designated by the numerals 2, 3 and 4, each of which is shown connected to a phase winding of the rotor 5. At 6 I have indicated a switch in the form of a five point

drum controller equipped with segments connected together as at J, K and L and adapted to successively contact with conductors La, S, R', R², R³, R⁴, and R⁵. As indicated at 5 the phase windings of the rotor 60 are connected to their respective resistances by conductors a, b and c. The source of current is indicated at G, H and I.

The controller drum is adapted to turn in the direction of the dart, that is, from right 65 to left. When it is thrown on the first notch La and S and L' and S' are connected and the flow of the current is from G through La and S to the point S² on the stator and from I through L' and S' to S³ on the stator 70 and back through neutral N² to H, thus supplying the full line voltage to the primary or stator.

At this time the induced current set up in the rotor flows through the conductors 75 a, b and c, respectively, to resistance parts 2, 3 and 4. I have shown these parts of the resistance in Y connection by the conductors M, N, whereby the current passing through c to 4 may continue through M and 80 N to parts 3 and 2, and the same is true of the current passing through conductors a and b to parts 2 and 3 of the resistance.

It will be noted that resistance part 2 is of less ohmic value than parts 3 and 4, and 85 consequently is always unbalanced relatively to those parts during the operation of the switch.

On moving controller 6 to the second notch R' and R² are connected. This short circuit parts 3 and 4 at R¹⁰ and R¹² thus cutting out one of the sections of each of these parts and connecting the resistance parts in parallel and in series with part 2. At this time the current is from part 4 95 through R¹², R², R' and R¹⁰ of part 3 and entirely through part 2 over M and N to 3 and 4.

On the third notch R³ is brought into contact while R' and R² are still in circuit. 100 R³ is connected with point R¹³ on resistance part 2. At this time the flow of the current is through parts 3 and 4, as described with reference to the second notch, and to R¹³ of part 2, cutting out a section of this part.

On the fourth notch R⁴ and R¹⁴ are connected and R⁴ is connected with R¹⁵, cutting out another section of parts 3 and 4. The resistance remaining below the parts R¹³, 105 R¹⁴, R¹⁵ after the switch has been fully 110

turned on to the fifth point, constitutes a permanent secondary resistance which may be maintained in the motor.

I claim as my invention:

5. 1. In a polyphase induction motor having phase windings always in circuit, a resistance in circuit with each phase winding, a switch for controlling said resistance parts, and means for constantly maintaining said 10 resistance parts relatively unequal or unbalanced in the operation of said switch.
15. 2. In a polyphase induction motor having phase windings always in circuit, a resistance in circuit with each phase winding, all 15 of said circuits not having the same degree of resistance, a switch for cutting out said several resistances, and conductors leading from each of said resistance parts to points on said switch to maintain the inequality of 20 said resistance parts from the first notch throughout the operation of said switch.
25. 3. In a polyphase induction motor, the combination with the rotor and a switch, of a plurality of resistance parts each in circuit with a phase winding of the rotor, said parts being of unequal ohmic values, and

means operated by said switch for cutting out sections of a plurality of parts on a predetermined notch while maintaining the full resistance of another resistance part.

30. 4. In a polyphase induction motor, the combination with a switch, of a plurality of resistance parts connected together in series and each of said parts connected to a phase winding of the rotor, said parts being 35 of different ohmic values, and means rendered effective at a predetermined notch of said controller for connecting said resistance parts in parallel.

40. 5. In a polyphase induction motor having phase windings, a resistance in circuit with each phase winding of the rotor, a switch for controlling said resistance parts, and means for shifting the resistance from one phase circuit to another.

45. In testimony whereof, I have signed this specification in the presence of two subscribing witnesses.

RICHARD VAN RENSSELAER SILL.
